UNITED STATES PATENT OFFICE

ANTONIO SALARI, OF BISBEE, ARIZONA, ASSIGNOR OF ONE-HALF TO WILLIAM LEDGERWOOD, OF BISBEE, ARIZONA.

FLOWER-HOLDER.

1,135,401.

Specification of Letters Patent. Patented Apr. 13, 1915.

Application filed July 20, 1914. Serial No. 352,038.

To all whom it may concern:

Be it known that I, ANTONIO SALARI, a citizen of the United States, residing at Bisbee, in the county of Cochise and State of Arizona, have invented certain new and useful Improvements in Flower-Holders, of which the following is a specification, reference being had to the accompanying drawings.

10 This invention relates to certain improvements in flower holders and has relation more particularly to a device of this general character especially adapted to be connected to a garment or the like; and an object of 15 the invention is to provide a device of this general character having novel and improved means whereby a flower may be positioned within the holder with convenience and facility and whereby the requisite moisture may be supplied to the flower in order 20 to prolong the life thereof.

Furthermore, it is an object of the invention to provide a device of this general character having novel and improved means 25 whereby the liquid, carried thereby, is effectively held against escape and thus avoiding the possibility of soiling the garment to which the holder is attached.

The invention consists in the details of 30 construction and in the combination and arrangement of the several parts of my improved flower holder, whereby certain important advantages are attained and the device is rendered simpler, less expensive 35 and otherwise more convenient and advantageous for use, all as will be hereinafter more fully set forth.

The novel features of the invention will be carefully defined in the appended claims.

40 In order that my invention may be the better understood, I will now proceed to describe the same with reference to the accompanying drawings, wherein—

Figure 1 is an elevational view of a holder 45 constructed in accordance with an embodiment of my invention; a second position of the hinged section of the neck being indicated by dotted lines; Fig. 2 is a rear elevational view of the device as embodied in 50 Fig. 1; Fig. 3 is an enlarged fragmentary view in top plan of the device as disclosed herein; and Fig. 4 is a sectional view taken substantially on the line 4—4 of Fig. 3.

As disclosed in the accompanying draw-

ings, 1 denotes a receptacle of any predetermined design provided adjacent one end with the elongated tubular stem or neck 2 in communication with the receptacle and through which is adapted to be directed the stem of a flower so that such stem may enter 60 within the receptacle 1 in order to receive the fluid adapted to be inserted within the receptacle through such neck.

As herein set forth, the neck 2 is divided longitudinally into the fixed section 3 and 65 the movable section 4 hingedly connected, as at 5, with the fixed section and adapted to be maintained in closed position through the medium of the coacting locking means 6 carried by the sections 3 and 4. As the locking 70 means may be of any arrangement desired, it is thought that a detailed description thereof is unnecessary.

Each of the sections 3 and 4 is provided with a lining 7 of compressible material 75 adapted to yieldably engage the stem of a flower without injuring the same and yet having sufficient contact therewith to maintain the flower against displacement. The lining 7 of the movable section 4 overlaps 80 the inner and longitudinal edge thereof, as indicated at 8, whereby it will be readily perceived that when the movable section 4 is adjusted into closed position, such lining serves as an effective medium to prevent 85 moisture from escaping from within the receptacle 1, which would otherwise tend to soil the garment to which the device may be attached. To one face of the receptacle 1 is suitably connected a pin 9 of conventional 90 form adapted to serve as a medium whereby the receptacle may be attached to a garment, as is believed to be clearly apparent to those skilled in the art to which my present invention appertains.

95 From the foregoing description, it is thought to be obvious that a flower holder constructed in accordance with my invention is of an extremely simple and comparatively inexpensive nature and is particularly well adapted for use by reason of the convenience and facility with which it may be assembled, and it will also be obvious that my invention is susceptible of some change and modification without material 100 departure from the principles and spirit thereof and for this reason I do not wish to be understood as limiting myself to the pre-

cise arrangement and formation of the several parts herein shown in carrying out my invention in practice.

I claim:

1. A device of the character described comprising a receptacle provided with a tubular neck in communication therewith, said neck being divided longitudinally into hingedly connected sections, and means for holding said sections in closed relation.

2. A device of the character described comprising a receptacle provided with a tubular neck in communication therewith, said neck being divided longitudinally into hingedly connected sections, means for holding said sections in closed relation, and a lining of yieldable material for each of said sections.

3. A device of the character described comprising a receptacle provided with a tubular neck in communication therewith, said neck being divided longitudinally into two sections, one of said sections being fix-

edly secured to the receptacle and the second section being hingedly connected with the first section, and means for maintaining the sections in closed relation.

4. A device of the character described comprising a receptacle provided with a tubular neck in communication therewith, said neck being divided longitudinally into two sections, one of said sections being fixedly secured to the receptacle and the second section being hingedly connected with the first section, means for maintaining the sections in closed relation, and a lining for each of the sections, the lining for the hinged section overlying the lower and longitudinal edges thereof.

In testimony whereof I hereunto affix my signature in the presence of two witnesses.

TONY SALARI.
